UNITED STATES PATENT OFFICE.

AUGUST F. PFEIFER, OF NEWARK, NEW JERSEY.

DESIGN FOR METAL TUBING.

SPECIFICATION forming part of Design No. 16,763, dated June 29, 1886.

Application filed May 22, 1885. Serial No. 166,398. Term of patent 7 years.

To all whom it may concern:

Be it known that I, AUGUST F. PFEIFER, of Newark, in the county of Essex and State of New Jersey, have invented a new and original Design for Tubing, of which the following is a full, clear, and exact description.

This invention relates to a design for tubing; and it consists of spiral ribs and intermediate grooves of equal width between the ribs.

10 The nature of my design is clearly shown in the accompanying drawings, in which Figure 1 represents a side view of a tube made according to my design; Fig. 2, a vertical longitudinal section, and Fig. 3 a vertical trans-

15 verse section on line $x-x$, Fig. 2.

Similar letters of reference indicate corresponding parts.

A in the drawings represents a tube, provided with spiral ribs a and intermediate spiral grooves, b , of equal width with the ribs a , whereby the appearance of a tube twisted bodily on its axis is imparted.

I am aware that metal tubes composed of several strands twisted together have been in use heretofore, and I do not claim the same. 25

Having thus described my design, I claim as new and desire to secure by Letters Patent—

The design for a tube, substantially as herein shown and described, the same consisting of 30 the spiral ribs, the grooves between the ribs being of the same width as said ribs, the sides of the grooves being concave and the sides of the ribs convex.

In testimony that I claim the foregoing as 35 my invention I have signed it this 11th day of May, 1885.

AUGUST F. PFEIFER.
